UNITED STATES PATENT OFFICE.

CHARLES HIRSCH, OF BUFFALO, NEW YORK.

IMPROVEMENT IN LUBRICATING DEVICES.

Specification forming part of Letters Patent No. 124,954, dated March 26, 1872.

SPECIFICATION.

I, CHARLES HIRSCH, of the city of Buffalo, in the county of Erie and State of New York, have invented an Improved Lubricating-Pump, of which the following is a specification:

My improvements relate more particularly to that class of pumps which are used for lubricating steam-engines; and the invention consists in the peculiar construction and arrangement of the parts whereby the oil-cup, pump-barrel, and discharge-pipe are enabled to be cast in one piece; and also in the special arrangement of the valves and oil-passages.

In the accompanying drawing, Figure I is a longitudinal section, and Fig. II a plan view of my improved pump. Fig. III is a cross-section in line x x , Fig. I.

Like letters designate like parts in each of the figures.

A is the oil-cup, preferably of the form of an oblate spheroid; B, the pump-barrel, which projects both outside and inside of the cup. The inner end of this pump-barrel connects at right angles with a hollow portion or pipe, C, which forms the valve-chamber c and oil induction-passage c' , the latter being an extension of the valve-chamber into which the pump-barrel opens. To the opposite side of the valve-chamber connects the discharge-pipe P, which extends outward through the opposite end of the oil-cup from that of the pump-barrel; the latter and the discharge-pipe both being in line of the longer diameter of the oil-cup. The above specified parts, by the use of the proper cores, are all cast entire or in one piece. The hollow pipe or casting C does not extend quite to the bottom of the cup, leaving sufficient space between its lower end and the cup for the flow of the oil into the induction-passage c' . At the upper end of the passage c' is arranged a check-valve, d , which prevents the reflux of the oil from the valve-chamber. d' is a similar valve at the top of the valve-chamber, which prevents the oil, after it has entered the space above this valve, from flowing back. Above the valve d' is a passage, e , opening into the discharge-pipe. The top of the valve-chamber is closed by a screw-plug, s .

F is a stop-cock connection, fastened firmly in place at any convenient point by means of screws and a flange, f , cast therewith. f^1 is the stop-cock, and f^2 f^3 two nozzles. To the nozzle f^3 a pipe may be made to connect with the engine at any required point. The pump is readily connected with the nozzle f^2 , when desired, by means of a thread cut on the projecting end or nozzle of the discharge-pipe. The plunger of the pump is made solid, as shown, with end slightly enlarged, and is retained in the barrel by a nut or collar, h , which screws onto the end of the pump-barrel, as clearly shown in Fig. I. The oil-cup is provided, at its top, with an opening, in which is screwed a flanged strainer, g , through which the oil is strained as it is supplied to the cup. The cup A being filled with oil, the operation of the pump becomes obvious from the foregoing description.

By my improved mode of construction, a pump can be made at a comparatively small cost, which will be efficient in its operation and not liable to get out of order. The stop-cock connection enables the pump to be used at the most convenient point away from the heat of the engine, and can be readily detached, when required, by simply closing the cock f^1 .

What I claim as my invention is—

1. The combination of the cup A, pump-barrel B, hollow casting C, and discharge-pipe P, arranged as described, and capable of being cast in one piece, substantially as hereinbefore set forth.
2. The arrangement, with the cup A, pump-barrel B, and discharge-pipe P, of the valves d d' , screw-plug s , and induction-pipe c , as shown and described.
3. The combination, with a detachable lubricating-pump, of the stop-cock connection F f f^1 f^2 f^3 , secured rigidly in place and forming a support for the pump when connected therewith, as hereinbefore set forth.

C. HIRSCH.
